No. 784,203.

PATENTED MAR. 7, 1905.

J. BINNIG.

ORGAN.

APPLICATION FILED JAN. 23, 1903.

UNITED STATES PATENT OFFICE.

JACOB BINNIG, OF BOSTON, MASSACHUSETTS, ASSIGNOR OF ONE-HALF
TO MASON & HAMLIN COMPANY, OF CAMBRIDGE, MASSACHUSETTS, A
CORPORATION OF DELAWARE.

ORGAN.

SPECIFICATION forming part of Letters Patent No. 784,203, dated March 7, 1905.

Application filed January 23, 1903. Serial No. 140,286.

To all whom it may concern:

Be it known that I, JACOB BINNIG, a citizen of the United States, residing at Boston, county of Suffolk, State of Massachusetts, have invented an Improvement in Organs, of which the following description, in connection with the accompanying drawings, is a specification, like numerals on the drawings representing like parts.

10 This invention relates to organs, and has especial reference to the valve which controls the communication between the register wind-chest and the sound-producing device or devices; and the object is to secure a valve which 15 will be simple and inexpensive to manufacture and which will operate to admit the air to the sound-producing device with the freedom necessary to make the instrument most effective.

In the embodiment of my invention which 20 I have herein illustrated the valve comprises a flexible diaphragm which extends across the usual valve-chamber, which is located between the usual register wind-chest and the sound-producing device, and said diaphragm 25 coacts with a valve-seat which is made by an annular lip or flange which surrounds the port leading from the wind-chest into the valve-chamber and which extends into the valve-chamber. The result is a valve in which the 30 valve-seat is situated some distance from the side of the valve-chamber. With this construction whenever the valve, whether it be in the nature of a diaphragm or of any other construction, is raised from its seat the air is permitted to flow freely from the wind-chest to 35 the sound-producing device.

In the drawings, Figure 1 is a vertical sectional view through certain parts of the organ, showing my improved construction; and 40 Fig. 2 is an enlarged partial section on substantially the line *xx*, Fig. 1.

3 designates the usual register wind-chest, which may be of any usual or suitable construction and which will either be connected 45 to a force-bellows or a suction-bellows, according to the particular type of organ in which my improvements are used.

4 indicates a sound-producing device, which

may be of any suitable or usual construction, though that herein illustrated is in the nature 50 of one of the pipes of a pipe-organ. This invention, however, can be used in connection with other sound-producing devices without changing its mode of operation.

Between the sound-producing device and 55 register wind-chest is the usual valve-chamber 5, in which is situated the valve for controlling the communication between said parts, it being understood that the valve-chamber is connected to the sound-producing 60 device by a port 6 and also with the wind-chest by a port 7. My invention relates particularly to the construction of the valve, which will now be described.

Extending across the valve-chamber and 65 dividing it into compartments 8 and 9 is a flexible diaphragm 10 of some suitable material—such as sheepskin, leather, &c. This diaphragm coacts with a valve-seat 11, shown in this embodiment of my invention as in the 70 form of an annular lip or flange 12, which surrounds the port 7 and projects from the wall of the valve-chamber and into the latter. This lip or flange may either be integral with the valve-chamber wall or may be 75 formed by the projecting end of a bushing 13, which is fitted to said port. The compartment 8 of the valve-chamber communicates through a suitable port or duct 14 either with the atmosphere or with an action wind-chamber, as 80 determined by any usual valve, one form of which will be presently described. The air-pressure in the register wind-chamber 3 is normally slightly less than that in the action wind-chamber 19, and under normal conditions the compartment 8 of the valve-chamber 85 will have communication with the action wind-chamber. Under these conditions the valve 10 will be held to its seat, as shown at the left, Fig. 1, and communication between the 90 register wind-chamber and the sound-producing device will be closed. When, however, the key of the organ corresponding to the sound-producing device 4 is operated, the compartment 8 of the valve-chamber will be 95 open to the atmosphere and the pressure there-

in relieved. As a consequence the greater pressure in the wind-chest 3 will lift the valve from its seat, as shown at the right, Fig. 1, thus allowing air to pass from the wind-chamber 3 to the sound-producing device. Since the valve is situated some distance from that wall of the valve-chamber which is adjacent the wind-chest 3, the air can flow freely over the valve-seat 11 into the compartment 9 of said valve-chamber and thence to the sound-producing device.

The mechanism for controlling the air-pressure in the compartment 8 may be of any suitable or usual type. As herein illustrated the duct 14 opens into a chamber 15, having a port 16 leading to the atmosphere and a port 17 leading into active wind-chamber 19, which is connected with the bellows by a pipe 20 and which contains the pneumatic 18 for operating the valves 21 and 22, which control the ports 16 and 17, respectively. The pneumatic is connected by a suitable pipe 23 and port 24 with an action wind-chamber 25, which will be connected to a suitable force-bellows. A spring-pressed valve 28 normally covers the port 24, and said valve is connected, through suitable lever mechanism 29, to one of the ordinary manual-keys 30. With this construction it will be observed that whenever the key 30 is depressed the valve 28 will be opened and air-pressure admitted to the pneumatic or motor 18 from the chamber 25. The expanding of the pneumatic will raise the valves 21 22, thus closing the port 17 and opening the port 16, as indicated at the right, Fig. 1. This places the compartment 8 of the valve-chamber in communication with the atmosphere and relieves the pressure therein, thus allowing the valve 10 to open, as above described.

In constructing the organ there will be a valve-chamber 5 for each pipe of each register or series of pipes, and preferably these valve-chambers will be formed in a plank or board 30^a, which extends across the front of the organ, said plank or board having in its upper edge the ports 6, to which the sound-producing devices or pipes are connected. In most pipe-organs a plurality of series or 45 registers of pipes are employed, and when such is the case I will preferably arrange the valve-chambers as shown in Fig. 1—that is, the valve-chambers for two adjacent series of pipes will be placed back to back and the 50 compartments 8 of the opposing chambers of the two series will open into the same duct 14. It is necessary, however, in this case to employ a separate register wind-chest 3' for the second series of sound-producing devices 4'.

4^a and 4^b designate two other series or registers of sound-producing devices, and 3^a and 3^b are the corresponding register wind-chests. The valve and valve-chamber between each 55 of these wind-chests and the corresponding

sound-producing device have the same construction as that already described, and the valve mechanism for controlling the air-pressure in the compartments 8 is similar to that already described.

The novel feature of this invention resides in a construction in which the valve-seat is situated between the opposite walls of the valve-chamber, so that when the valve is raised from its seat the air can flow through the valve-chamber with the greatest possible freedom. It will be obvious, therefore, that many changes may be made in the construction herein shown without departing from the invention.

Having described my invention, what I claim as new, and desire to secure by Letters Patent, is—

1. In an organ, a sound-producing device, a valve-chamber communicating therewith, a wind-chest, a port leading from said wind-chest and terminating in an annular valve-seat which is located between the opposite walls of said valve-chamber, and a valve in said chamber to coact with said seat to control the communication between the wind-chest and the sound-producing device.

2. In an organ, a sound-producing device, a valve-chamber communicating therewith, a wind-chest, a port leading from said wind-chest and terminating in an annular valve-seat which is located between the opposite walls of said valve-chamber, and a diaphragm-valve in said chamber to coact with said seat to control the communication between the wind-chest 95 and the sound-producing device, said valve being spaced from the walls of said chamber.

3. In an organ, a sound-producing device, a valve-chamber communicating therewith, a diaphragm-valve extending across said valve-chamber and located between and spaced from the opposite walls thereof, a port connecting the wind-chest and valve-chamber and terminating in a valve-seat coacting with said valve to control the communication between the wind-chest and sound-producing device, said valve-seat being situated between the planes of said walls of the valve-chamber.

4. In an organ, a sound-producing device, a valve-chamber, a flexible diaphragm extending across said chamber and dividing it into two compartments one of which communicates with the sound-producing device, a wind-chest, a port connecting the wind-chest and said last-named compartment of the valve-chamber, and terminating in a valve-seat located between the planes of the opposite walls of the valve-chamber and adapted to coact with the diaphragm, and means to control the air-pressure in the other compartment of the valve-chamber.

5. In an organ, a wind-chest, a valve-chamber, a sound-producing device communicating with the valve-chamber, a port connecting the wind-chest and the valve-chamber, an annular lip or flange surrounding said port and pro-

jecting into the valve-chamber, the end of said lip or flange constituting a valve-seat, and a valve to engage the seat and cut off communication between the wind-chest and sound-producing device.

6. In an organ, a wind-chest, a valve-chamber, a sound-producing device communicating with the valve-chamber, a port connecting the wind-chest and the valve-chamber, an annular lip or flange surrounding said port and projecting into the valve-chamber, the end of said lip or flange constituting a valve-seat, and a diaphragm-valve located between the opposite walls of the valve-chamber to engage the seat and cut off communication between the wind-chest and sound-producing device.

7. In an organ, a sound-producing device, a wind-chest, a valve-chamber, a diaphragm extending across and dividing said chamber into two compartments, one of which communicates with both the sound-producing device and the wind-chest, a lip or flange surrounding the port between the valve-chamber and wind-chest, and projecting into the valve-chamber, the end of said lip or flange constituting a valve-seat against which the diaphragm is adapted to seat to cut off communication between the wind-chest and sound-producing device.

8. In an organ, a sound-producing device, a wind-chest, a valve-chamber, a diaphragm extending across and dividing said chamber into two compartments one of which communicates with both the sound-producing device and the wind-chest, means to control the wind-pressure in the other of said compartments, a lip or flange surrounding the port between the wind-chest and valve-chamber and projecting into the latter, the end of said lip or flange constituting a valve-seat against which the diaphragm is adapted to seat to cut off communication between the wind-chest and sound-producing device.

9. In an organ, a wind-chest, a valve-chamber, a sound-producing device connected with

the valve-chamber, a port connecting the wind-chest and valve-chamber, a bushing in said port and extending into the valve-chamber, and a diaphragm-valve separated from the walls of the valve-chamber and adapted to be seated on the end of said bushing, said valve operating to control communication between the wind-chest and sound-producing device.

10. In an organ, a sound-producing device, a wind-chest, a valve-chamber having opposite parallel walls, a diaphragm extending across said chamber parallel to said walls and dividing the chamber into two independent compartments, a port connecting one compartment of the valve-chamber with the sound-producing device, another port connecting said compartment with the wind-chest, an annular flange surrounding said latter port and projecting into the valve-chamber and terminating in a valve-seat with which the diaphragm coacts.

11. In an organ, two sound-producing devices, a wind-chest, and a valve-chamber for each sound-producing device, a diaphragm extending across each valve-chamber and dividing it into two compartments, one compartment of each chamber communicating with the corresponding sound-producing device and also with the corresponding wind-chest, the other compartments of said valve-chambers communicating with each other, means to control the air-pressure in said last-named compartments, and a lip or flange surrounding the port leading from each wind-chest to the corresponding valve-chamber, and projecting into the latter, the end of said lip or flange constituting a valve-seat for the diaphragm.

In testimony whereof I have signed my name to this specification in the presence of two subscribing witnesses.

JACOB BINNIG.
